MECHANICAL POWER SHOVEL

Charles E. Stoltz, Chicago, Ill., assignor to Mancha Storage Battery Locomotive Company, Chicago, Ill., a corporation of Illinois

Application April 22, 1935, Serial No. 17,597

8 Claims. (Cl. 214—131)

This invention relates to improvements in mechanical power shovels of the mucking type adapted to shovel in mines under ground and discharge the material shoveled into a car or like receptacle disposed rearwardly thereof.

Among the objects of my invention are to provide a new and improved mucking machine of a size which may readily be transferred from one level of the mine to another in a mine cage, which machine is arranged with a view towards efficiency in operation and compactness, especially in longitudinal and lateral dimensions. Another object of my invention is to provide a novel means for moving the forward or ground engaging end of the scoop longitudinally forwardly of the truck for gathering material, together with a new and improved means for controlling this longitudinal movement of the scoop and movement thereof to a discharge position.

20 A prior application, Serial No. 17,419, filed April 20, 1935, discloses a device similar to that shown by my present invention. My present invention, however, differs from my prior invention in that a different means is shown for operating and controlling operation of the scoop and in that a different centering mechanism operating on different principles from that shown in my prior application is disclosed.

My invention may be more clearly understood 30 with reference to the accompanying drawings, wherein:

Figure 1 is a side elevation of a power shovel constructed in accordance with my invention with certain parts broken away and shown in 35 longitudinal section;

Figure 2 is a top plan view of the machine shown in Figure 1 with certain parts broken away and shown in section;

Figure 3 is a transverse sectional view taken 40 substantially along line 3—3 of Figure 1;

Figure 4 is a sectional view taken substantially along line 4—4 of Figure 1;

Figures 5 and 6 are sectional views of one of 45 the valves for controlling operation of the machine, showing the valve in different operating positions;

Figure 7 is a sectional view taken substantially along line 7—7 of Figure 5;

50 Figure 8 is a detail view showing one means of operating the valve illustrated in Figure 5;

Figure 9 is a fragmentary top plan view of the machine shown in Figure 1, with the shovel frame positioned to one side of the center line 55 of the truck and with the shovel and supporting

beams therefor broken away, to illustrate certain details of the centering mechanism;

Figure 10 is a fragmentary horizontal sectional view showing certain details of the centering mechanism, not shown in Figure 9; and

Figures 11 and 12 are diagrammatic views showing certain stages of the operating cycle of the machine illustrated in Figure 1.

Like reference characters refer to like parts throughout the various figures.

In the drawings, the embodiment of my invention illustrated includes a truck 10 which comprises a frame 12 mounted on track wheels 14, 14 and axles 15, 15 in a suitable manner. A turntable or shovel supporting frame 17 is 15 mounted on said truck frame for movement with respect thereto about a vertical axis disposed adjacent the center of said truck frame. Said turntable forms a supporting means for a scoop 18 and the operating mechanism therefor.

The machine is propelled along the rails from working place to working place and fed into the material it is desired to load during the gathering and loading operations by means of a suitable motor 20 mounted on and extending downwardly 25 from the truck frame 12. Said motor may be of any type well known to those skilled in the art, but is herein preferably shown as being an air motor of an ordinary construction. The drive from said motor to the track wheels includes a 30 chain and sprocket drive generally indicated by reference character 21, operatively connected with the front track wheels, and a chain and sprocket drive generally indicated by reference character 23, connected between the front and 35 rear track wheels. The machine may thus be readily moved from working place to working place.

The turntable or shovel frame 17 includes a 40 plate 24 pivotally mounted on a boss 25 extending upwardly from the truck frame 12 adjacent the center thereof, and side plates 26, 26 extending upwardly from opposite lateral sides of said plate. The under side of said plate is supported on suitable balls carried in an annular race or 45 guideway 29 having an outer diameter substantially equal to the width of said truck frame. A retaining plate 30 is secured to the top of said boss by means of suitable cap screws, and abuts the upper surface of the plate 24 to hold said plate from upward movement with respect to said boss.

The scoop 18 is supported on the turntable 17 by means of a pair of parallel-spaced beams 31, 31. Said beams are freely mounted on a trans-

verse shaft 33 which shaft, as herein shown, is mounted adjacent its ends in the hubs of parallel-spaced vertically disposed gear sectors 34, 34. Said gear sectors are arranged inwardly of the side plates 26, 26 and are secured to the bottom plate 24. Said shaft is so arranged that its longitudinal center line is adjacent but rearwardly of the transverse center line of said turntable.

The scoop is provided with a bracket 35 extending rearwardly therefrom adjacent the upper end thereof. The outer sides of said bracket are adapted to abut the inner sides of the beams 31, 31 adjacent the free ends thereof and said bracket is pivotally secured to said beams by means of a transverse shaft 36 extending therethrough and held from lateral movement with respect thereto in a suitable manner. Said scoop depends from the free ends of said beams when extending forwardly of said frame and a forward digging edge 37 of said scoop is adapted to engage and be slidably moved along the ground.

Suitable means are provided for pivoting the scoop about its axis of pivotal connection to said beams and moving said scoop longitudinally forwardly of the truck along the ground, which means, as herein shown, comprises a cylinder 38 pivotally connected between said beams rearwardly of the forward end thereof, and a piston 39 carried therein and pivotally connected to said scoop at a point disposed a substantial distance beneath the shaft 36 when said scoop is positioned as is shown in Figure 1. Said cylinder is provided with an upstanding lug 40 disposed adjacent the rearward end thereof, which lug is pivotally mounted on a transverse shaft 41. Said shaft is journaled in and extends beyond the outer sides of said beams, and has a pair of spur gears 43, 43 secured to the outer ends thereof which mesh with the teeth of the gear sectors 34, 34 for swinging said beams about their axis of pivotal connection to said turntable, in a manner which will hereinafter be more fully described.

The piston 39 is provided with a forwardly extending piston rod 44 which has its free end pivotally connected to a transverse shaft 45. Said shaft is mounted in a pair of parallel-spaced brackets 41, 41 extending rearwardly from said scoop and spaced beneath the bracket 35 a substantial distance when the forward end of said scoop is positioned adjacent the ground. Said shaft extends beyond said brackets and beyond the sides of said scoop and has rollers 48, 48 journaled on its ends which are adapted to engage guide cams 49, 49 secured to and extending inwardly from the side plates 26, 26 to form a means for supporting said scoop during the discharge operation, in a manner similar to that described in my aforementioned prior application.

The outer side of said cylinder is provided with oppositely disposed laterally extending projections 50, 50 extending longitudinally therealong which are adapted to be engaged by slots 51, 51 formed in guiding members 53, 53 pivotally mounted on the shaft 45 for guiding said cylinder.

The means for swinging said beams about the axis of the shaft 33 includes a motor 54 mounted on the turntable adjacent the rearward end thereof. Said motor is herein preferably shown as being a motor of the fluid pressure type and is provided with a motor shaft 55 having a sprocket 57 secured thereto. Said sprocket drives a sprocket 59 keyed to the transverse shaft 33 through a drive chain 60. A sprocket 61 is disposed adjacent the sprocket 59, and is herein shown as being formed integral therewith. The sprocket 61 is

operatively connected with the transversely disposed shaft 41 for rotating said shaft and the spur gears 43, 43 by means of a chain and sprocket drive, generally indicated by reference character 63. Thus, when the motor is driven in one direction, said spur gears travel along the teeth of said gear sectors and pivot said beams in an upward direction to elevate the scoop above the ground and move it toward the rearward end of said truck, and said spur gears move said scoop in an opposite direction to an initial loading position when said motor is reversely driven.

The motor 54 and cylinder 38 are controlled through a single operating lever by a novel valve arrangement which consists of a valve 64a which controls starting and stopping and reversing of the motor, and a valve 64b which controls the admission of pressure into or the release of pressure from the cylinder 38. Said valves are best illustrated in Figures 5, 6 and 7, and as herein shown, include an upper body portion 65 and a lower body 66 threaded therein. Said upper body is provided with a conical bore which converges towards its upper end and has a frusto conical plug 67 rotatably mounted therein. Said plug 67 has a valve stem 69 passing therethrough and freely mounted therein which stem is a portion of the valve 64b. A port 70 in the form of a segment of an annular ring is formed in said plug and communicates with a high pressure line 71. When said plug is positioned as shown in Figure 7, the valve 64a is in a closed position, and when turned in one direction pressure is permitted to enter a pressure line 73 for driving the motor in one direction, and when turned in an opposite direction pressure is permitted to enter a pressure line 74 for driving said motor in an opposite direction.

The valve stem 69 extends into a chamber 75 of the valve 64b and has a port 76 communicating with the port 70 in the plug 67 and the supply line. The port 76 communicates with a port 77 in a tapered plunger 79 secured to the lower end of said valve stem. Said plunger is adapted to engage a frusto conical bore of a frusto conical plug 81. Said plug is movable within a frusto conical portion 83 of the chamber 75. An exhaust port 84 communicates with the chamber 75 and is closed by the plug 81 when moved upwardly by means of a spring 85 engaging the under surface thereof. A pressure outlet 87 communicates with a pressure line 88 which line in turn communicates with the cylinder 38. It may thus be seen that pressure is admitted to said pressure line when the valve stem 69 is moved in an upward direction against a compression spring 89 to the position shown by dotted lines in Figure 5, in which position the exhaust port 84 is closed by the plug 81 and said plunger is unseated from said plug.

An operating lever 90 is pivoted intermediate its ends on a bracket 91 secured to and extending from the upper end of the plug 67. Said bracket is keyed to said plug so that pivotal movement thereof will pivot said plug. Said lever has a bifurcated end which engages a collar 93 mounted in a groove 94 in the upper end of the valve stem 69. Thus, pivotal movement of said operating lever about one axis will pivot the plug 67 to operate the motor 54 and pivotal movement of said operating lever about its axis of pivotal connection to the bracket 91 will raise or lower said valve stem to admit pressure to or release pressure from the cylinder 38.

When the beams 31, 31 are in the position illus-

trated in Figure 1, pressure is usually applied to the cylinder 38 to extend the piston rod 44 therefrom and pivot the scoop about its axis of pivotal connection to said beams and move said scoop longitudinally forward of the truck. At the same time the motor is started and said beams and scoop are moved in an upward direction, pressure being held in said cylinder during such upward movement until the rollers 48, 48 on the ends 10 of the shaft 45 engage the supporting guides 49, 49.

Pressure is released from the cylinder 38 at a predetermined point by means of a cam member 99 keyed to the shaft 33 inwardly of the right hand arm 31. Said cam member is adapted to engage an inwardly extending end of a depending lever arm 100 pivoted to the right hand side plate 26 at a point spaced from but adjacent and in alignment with the upper end of the valve stem 69. An arm 101 is formed integral with 20 and extends forwardly from the upper end of said lever arm and engages the upper end of the valve stem 69 for operating the valve 66. Thus, engagement of said arm by said cam moves 25 said valve stem in a downward direction to the position shown in Figure 6, for exhausting pressure from the cylinder 38 and permitting said rollers to ride on and support the forward end 30 of the scoop on the supporting guides 49, 49. The relationship of said cam with respect to said beam is such that pressure is exhausted from said cylinder when said rollers are at the forward end 35 of said supporting guides.

The supporting guides or cams 49, 49 are inclined upwardly towards the rearward end of the side plates 26, 26 in a manner similar to that disclosed in my aforementioned prior application. Thus, movement of said beams from the point where pressure is exhausted from the 40 cylinder 38 causes the forward or gathering end of said scoop to be moved to an elevated position for the discharge of material from the rearward end thereof, as is illustrated by broken lines in Figure 1. At this position the rollers 48, 48

engage stops 103, 103. Said stops, as herein shown, are a continuation of supporting guides 104, 104 secured to and extending inwardly from the inner side of each side plate 26 beneath the supporting guides 49, 49. Said stops are pivoted 50 to said side plates by means of pivotal pins 105, 105 and their upper end is slidable in a guide 106. A compression spring 107 is interposed between a fixed lug 108 on each side plate and a lug 109 extending rearwardly from said stop to provide 55 a cushioning effect for said scoop at discharge.

Movement of said beams in a forward direction from the discharge position (indicated by broken lines in Figure 1) causes said scoop to be lowered along the supporting guides 104, 104 to an initial 60 gathering position, such as is illustrated by solid lines in Figure 1, in a manner similar to that described in my aforementioned prior application.

The distance of the engaging end of the scoop 65 above the ground may be adjusted by means of the piston 39 and supporting beams 31, 31. If desired, suitable adjustable stops may be provided for the supporting beams 31, 31 to form a positive means for stopping the forward end of 70 said scoop in the proper relationship with respect to the ground.

The turntable 17 is herein preferably shown 75 as being manually operated, and a hand grip 110 is provided for this purpose. Said hand grip, as herein shown, comprises a vertical shaft 111

mounted at its ends in brackets 112, 112 secured to and extending outwardly from the right hand side plate 26. A cylinder 113 closed at its ends encircles said shaft and forms a gripping means. Compression springs 114, 114 are interposed between a stop 115 secured to the center of said shaft and the closed ends of said cylinder, to permit said cylinder to be yieldably moved along said shaft and return it to a central position when hand pressure is released therefrom. An arm 116 extends from the lower closed end of said cylinder along the side plate 26 in a rearward direction and has an inwardly extending bifurcated end which extends through a vertical slot formed in said side plate. A valve operating lever 117 is pivotally mounted between said bifurcated ends of said arm and forms a means for operating a valve 118 for controlling operation of the motor 20. Said valve has pressure lines 119 and 120 leading therefrom which are connected to the motor 20 in such a manner that when air is admitted to the pressure line 119 said motor is rotated in one direction, and is reversed when air is admitted to the pressure line 120. Said valve is connected to the high pressure supply line by means of a pressure line 121. When the hand grip 110 is midway between the brackets 112, 112, the valve 118 is in a neutral position. When said hand grip is moved in an upward direction, the motor 20 is rotated in one direction and when it is moved to a lower position said motor is driven in an opposite direction.

It will be seen from the foregoing that the truck and scoop 18 may be controlled in a simplified manner with a minimum amount of controlling levers and that one handle serves to control longitudinal movement of the scoop and swinging movement of the scoop supporting beams, while another handle serves to swing the turntable in one direction or another and controls movement of the truck along the track in one direction or another.

Referring now in particular to the novel centering mechanism for aligning the turntable with the truck frame when the scoop is in a discharge position, the transverse shaft 33 has a threaded member 122 keyed thereon. Said threaded member extends between the beams 31, 31 and is threaded in opposite directions from the center thereof. A pair of nuts 123, 123 is threaded on said threaded member. Said nuts are adapted to move along said threaded member in opposite directions upon rotation of the shaft 33 in one direction and are positioned adjacent the insides of said beams when the scoop is in a lowered position. A lug 124 extends upwardly from the truck frame 12 through an arcuate slot 125 formed in the plate 24. Said lug is adapted to be engaged by depending projections 126, 126 from the nuts 123, 123. Thus, the turntable may be pivoted to one side or the other of the center line of truck until one of the depending projections 126 engages the lug 124. Upon movement of the beams 31, 31 in an upward direction, the shaft 33 and threaded member 122 will be driven by the motor in one direction which will cause the nuts 123, 123 to be moved toward the center of said shaft. As said nuts approach the center of said shaft, the depending projection 126 having engagement with the lug 124 will turn the turntable 17 so that its longitudinal center line approaches the longitudinal center line of the truck and said center lines will be aligned when said beams reach the extreme upper position 75

- illustrated in Figure 1. At this position both of the depending projections 126 will be in engagement with the lug 124 which will lock the turntable in an aligned position with respect to the truck. Rotation of said motor in an opposite direction, and corresponding rotation of said shaft and movement of said beams in an opposite direction, will cause said nuts to move outwardly along said shaft until positioned along the insides of said beams, at which point the scoop will be in the position illustrated by Figure 1, and the turntable will be free to move, so as to position said scoop to one side or the other of the track.
- 15 Suitable means are provided for locking the scoop in a retracted position with respect to the truck when it is desired to place it on a cage to be moved from one level in the mine to another. Said means, as herein shown, comprises a plurality of aligned apertures 127, 127 formed in the side plates 26, 26 between the supporting guides 49 and 104. Said apertures may be engaged by suitable pins, indicated by reference character 128 and shown in Figure 12, which pins are adapted to be positioned so as to engage the lower or forward sides of the brackets 47, 47 to permit said scoop to rest thereon and lock said scoop and the shovel operating mechanism so that it is entirely within the forward and rearward boundaries of said side plates.
- 20 While I have herein shown and described one form in which my invention may be embodied, it will be understood that the construction and arrangement of the various parts may be changed or altered without departing from the spirit or scope thereof. Furthermore, I do not wish to be construed as limiting myself to the precise construction illustrated, excepting as it may be limited in the appended claims.
- 25 40 I claim as my invention:
1. In an apparatus of the class described, a frame, a beam horizontally pivoted on said frame, a scoop pivoted on the free end of said beam and depending therefrom, means for swinging said beam, fluid pressure means operable independently of said beam swinging means for pivotally moving said scoop forwardly of said frame for engagement with a pile of loose material comprising a cylinder and piston interposed between said beam and scoop, means for applying pressure to said cylinder including a fluid pressure valve, and means operable upon movement of said beam to a predetermined position for operating said valve and releasing pressure from said cylinder.
  2. In an apparatus of the class described, a frame, a beam horizontally pivoted on said frame, a scoop pivoted on the free end of said beam and depending therefrom, means for swinging said beam, fluid pressure means operable independently of said beam swinging means for pivotally moving said scoop forwardly of said frame for engagement with a pile of loose material comprising a cylinder and piston interposed between said beam and scoop, means for applying pressure to said cylinder including a fluid pressure valve, and means operable upon movement of said beam to a predetermined position for operating said valve and releasing pressure from said cylinder.
  3. In a shoveling machine of the class described, the combination of a track-mounted

frame, a beam horizontally pivoted on said frame, a scoop pivoted on the free end of said beam and depending therefrom, a fluid pressure motor on said frame, a drive connection from said motor for swinging said beam including an arcuate rack and a gear on said beam driven by said motor and meshing therewith, fluid pressure means operable independently of said beam for moving said scoop forwardly of said frame for engagement with a pile of loose material comprising a cylinder and piston interposed between said beam and scoop and having pivotal connection with said scoop at a point disposed beneath the point of pivotal connection of said beam to said scoop, means for applying pressure to said cylinder including a fluid pressure valve, and means operable upon movement of said beam to a predetermined position for operating said valve and releasing pressure from said cylinder.

4. In a shoveling machine of the class described, the combination of a track-mounted frame, a beam horizontally pivoted on said frame, a scoop pivoted on the free end of said beam and depending therefrom, a fluid pressure motor on said frame, a drive connection from said motor for swinging said beam including an arcuate rack and a gear on said beam driven by said motor and meshing therewith, fluid pressure means operable independently of said beam for moving said scoop forwardly of said frame for engagement with a pile of loose material comprising a cylinder and piston interposed between said beam and scoop and having pivotal connection with said scoop at a point disposed beneath the point of pivotal connection of said beam to said scoop, means for applying pressure to said cylinder including a fluid pressure valve, and means operable upon movement of said beam to a predetermined position for operating said valve and releasing pressure from said cylinder comprising a cam member arranged coaxial with the axis of pivotal movement of said beam, and valve operating mechanism adapted to be engaged by said cam member.

5. In a shoveling machine of the class described, the combination of a truck, a beam horizontally pivoted on said truck, a scoop pivoted on the free end of said beam and depending therefrom, a fluid pressure motor on said truck, a drive connection from said motor for swinging said beam including an arcuate rack and a gear on said beam driven by said motor and meshing therewith, fluid pressure means operable independently of said beam for moving said scoop forwardly of said truck for engagement with a pile of loose material comprising a cylinder and piston interposed between said beam and scoop and having pivotal connection with said scoop at a point disposed beneath the point of pivotal connection of said beam to said scoop, means for applying pressure to said cylinder including a fluid pressure valve, another valve for operating said motor, and a common operating lever for said valves whereby both of said valves may be independently or simultaneously operated with one hand.

6. In a shoveling machine of the class described, a truck including a frame mounted on track wheels and axles, a turntable on said frame, a beam pivoted on said turntable for movement about a horizontal transverse axis disposed adjacent the central portion thereof, a scoop depending from and pivoted on the free end of said beam, a fluid pressure motor on said turntable, a drive connection from said motor

for swinging said beam including an arcuate rack and a gear journaled on said beam meshing therewith, a fluid pressure cylinder and piston interposed between said beam and scoop and 5 having pivotal connection with said scoop at a point disposed beneath the point of pivotal connection of said beam to said scoop for engaging said scoop with a pile of material, a fluid pressure motor on said truck for driving said truck 10 or holding said truck from movement during the loading operation, a valve for operating said motor, and means for operating said valve comprising a handle on said turntable, so arranged that pressure thereon in one direction will turn 15 said turntable, and pressure in another direction will operate said valve.

7. In a shoveling machine of the class described, a truck including a frame mounted on track wheels and axles, a turntable on said frame, 20 a beam pivoted on said turntable for movement about a horizontal transverse axis disposed adjacent the central portion thereof, a scoop depending from and pivoted on the free end of said beam, a fluid pressure motor on said turn- 25 table, a drive connection from said motor for swinging said beam including an arcuate rack and a gear journaled on said beam meshing therewith, a fluid pressure cylinder and piston interposed between said beam and scoop and 30 having pivotal connection with said scoop at a point disposed beneath the point of pivotal connection of said beam to said scoop for engaging said scoop with a pile of material, a pair of valves for operating said scoop and motor, an-

other fluid pressure motor on said truck for driving said truck or holding said truck from movement during the loading operation, a valve for operating said motor, a common operating lever for selectively operating said pair of valves with 5 one hand, and another operating member for turning said turntable and operating said second-mentioned valve with the other hand.

8. In a shoveling machine of the class described, the combination of a track-mounted 10 frame, a beam horizontally pivoted on said frame, a scoop pivoted on the free end of said beam and depending therefrom, a fluid pressure motor on said frame, a drive connection from said motor for swinging said beam including an arcuate 15 rack and a gear on said beam driven by said motor and meshing therewith, fluid pressure means operable independently of said beam for moving said scoop forwardly of said frame for engagement with a pile of loose material com- 20 prising a cylinder and piston interposed between said beam and scoop and having pivotal connection with said scoop at a point disposed beneath the point of pivotal connection of said beam to said scoop, means for applying pressure to said 25 cylinder including a fluid pressure valve, and means for operating said motor comprising another valve associated with said first-mentioned valve, said valves being arranged along a common valve stem, and a common operating member 30 for selectively operating both of said valves with one hand.

CHARLES E. STOLTZ.
